UNITED STATES PATENT OFFICE.

VINCENT P. TRAVERS, OF NEW YORK, N. Y.

HAMMOCK-SUPPORT.

SPECIFICATION forming part of Letters Patent No. 316,419, dated April 21, 1885.

Application filed May 16, 1884. (No model.)

To all whom it may concern:

Be it known that I, VINCENT P. TRAVERS, a resident of New York city, in the county and State of New York, have invented an Improved 5 Hammock-Support, of which the following is a full, clear, and exact description, reference being made to the accompanying drawings, in which—

Figure 1 is a perspective view of my improved hammock-support. Figs. 2, 3, 4, and 10 5 are detail views of parts thereof.

The object of this invention is to produce a structure within which hammocks can be suspended, such structure to be in no wise in the 15 way of a person approaching or using the hammock.

My invention consists in combining with a series of socket-pieces certain connecting-bars, wherefrom results a peculiar frame, within 20 which the hammock may be suspended, the whole device being simple in construction and economical.

In the drawings, the frame A, within which the hammock B is suspended, is shown to consist of the horizontal pieces *a a*, which rest on 25 the floor or ground, and of the converging pieces *b b*, that connect with the ends of the horizontal pieces *a a*, and sustain the booms *d d*, to which the hammock is tied. The bars *b b* flare outwardly, as shown in Fig. 1, and the booms *d d* project outwardly therefrom.

The bars *a a* are joined to the bars *b b* by the socket-pieces *e e*. These socket-pieces are more fully represented in Figs. 4 and 5, and consist each of a pair of metallic thimble-like 35 sockets, which are joined by a web, *f*. The smaller ends of these sockets are made to meet at the required angle, so that when the parts *a b* are inserted they will stand at the requisite angle. The socket-pieces *g*, for joining the 40 converging bars *b b* and boom *d*, are more fully shown in Figs. 2 and 3, and consist each of three thimble-like sockets of truncated conical form, or of pyramidal form, if desired, 45 the central socket having its mouth or opening in line with the closed or smaller ends of the outer sockets, as shown. The several sockets of the piece *g* are united by webs *h h*.

It will be seen that when this frame A, com-

posed of the pieces stated, is placed in position none of its parts will be in the way of any one coming near, passing by, or lying in the hammock, and in this respect my hammock-support differs, I believe, materially from any that have heretofore been devised, 50 in all of which projecting feet or braces rendered their use objectionable. I refer to such structures as are shown in Letters Patent No. 280,081. The whole frame A of my construction is practically beneath the hammock, and 55 yet it has great strength.

The bars *a b d* may be made of strong wood—such as hickory—or of metal, or of other analogous substance. By joining them by means of the socket-pieces *e g* the structure is made 60 separable, which renders it convenient for transportation. Still I do not wish to be confined to any particular mode of joining these sections, as the principal feature of my invention consists in the general form of the frame 65 A which I have shown, although the detailed construction I also regard as my invention.

I claim nothing shown in English Patent No. 2,916 of 1882.

I claim—
1. The hammock-frame A, composed of the horizontal bottom bars, *a a*, and converging outwardly-flaring end bars, *b b*, in combination with the outwardly-projecting end booms, *d d*, all the said parts being rigidly connected, 70 substantially as herein shown and described.

2. The combination of the bottom bars, *a a*, with the four separate socket-pieces *e e*, having webs *f*, and with the four converging and outwardly-flaring bars *b*, and two socket-pieces, *g g*, having webs *h*, substantially as described.

3. The combination of the bottom bars, *a a*, with the four socket-pieces *e e*, having webs *f*, and with the four converging outwardly-flaring bars *b*, the two socket-pieces *g g*, having webs *h*, and with the two outwardly-projecting booms *d*, substantially as described.

VINCENT P. TRAVERS.
